United States Patent Office.

JAMES GRAY, OF NEWARK, NEW JERSEY.

Letters Patent No. 79,067, dated June 23, 1868; antedated June 13, 1868.

IMPROVEMENT IN SAD-IRONS.

The Schedule referred to in these Letters Patent and making part of the same.

TO ALL WHOM IT MAY CONCERN:

Be it known that I, JAMES GRAY, of Newark, in the county of Essex, and State of New Jersey, have invented a new and improved Sad-Iron; and I do hereby declare that the following is a full, clear, and exact description thereof, which will enable others skilled in the art to make and use the same, reference being had to the accompanying drawings, forming part of this specification.

Figure 1 represents a longitudinal vertical section of my improved sad-iron.

Figure 2 is a vertical transverse section of the same.

Figure 3 is a plan or top view of the same, showing the cover turned back and the iron open.

Similar letters of reference indicate corresponding parts.

This invention relates to a new self-heating sad-iron, which is so arranged that the cover of the iron will remain cool, and so that the draught can at all times be regulated at will.

The invention consists in the use of a perforated bed, fixed stationary in the lower part of the hollow sad-iron, its interior communicating with the outside air by a hole in the side of the iron; the hole being arranged high enough to prevent the falling out of ashes.

The invention also consists in the use of a hinged or removable cover, which is made of two plates, having an air-space between them for the circulation of fresh air.

The said cover is thereby always kept cool, and with it the handle of the sad-iron.

The invention consists finally in the use of the damper, arranged below the lower entrance of the smoke-pipe, the said damper being operated by a pin fitting through a slot in the upper plate of the cover.

The draught can thereby be completely regulated.

A represents a hollow sad-iron, of suitable or ordinary form and material.

Above its bottom, near its rear or broad end, is arranged a perforated cap, B, which is firmly secured in the iron, and which acts as a grate for the fuel.

An air-hole, α , is made in the back or side plates of the iron to communicate with the interior of the cap, the said air-hole or holes being arranged high enough above the bottom of the iron to prevent the falling out of ashes.

The air entering through the hole α into the cap B, is fed to the fire through the holes in the cap, and supplies the same with the requisite amount of oxygen.

The products of combustion escape through a smoke-pipe, C, which is fixed on the cover of the iron.

The whole or part of the cover D of the sad-iron is hinged to or made removable from the body of the iron, and consists of two plates, b and c, one arranged above the other, so as to leave an air-space, d, between the same, as is clearly shown in figs. 1 and 2.

This air-space d does, when the whole cover fits upon the iron, allow the direct circulation of the air below the upper plate b of the cover, thereby keeping the said plate at all times cool, and with it the handle E of the iron, which is fixed to a standard or standards, F, projecting from the cover.

If the cover is so arranged that only its upper plate b fits upon and rests on the edges of the iron, so that the air-space is surrounded by the walls of the iron, then the said walls have to be perforated, as shown in fig. 1, to allow the circulation of air through the said space d for the aforesaid purpose.

Between the plates b and c is arranged a sliding plate, G, (see fig. 3,) which is provided with a projecting pin, e, projecting upward through a slot in the upper plate b.

This plate G can be moved, so as to close the lower end of the smoke-pipe C, more or less, and thus the draught can be regulated at will.

I am aware that the solid cap in the lower part of the sad-iron has been before known and used, but, as it has the tendency to heat the top of the iron instead of the bottom, I do not, therefore, claim it; but

I claim as new, and desire to secure by Letters Patent—

1. The cover D, constructed as described, consisting of the plates b c, forming a cold-air chamber, the upper plate being slotted for the passage of the arm e of the catch-damper G, as herein shown and described.

2. The adjustable sliding damper G, when arranged below or near the mouth of the smoke-pipe C of a hollow self-heating smoothing-iron, substantially as and for the purpose herein shown and described.
3. A self-heating smoothing-iron, when provided with a perforated cap fixed in the interior of the hollow iron, with a double cover, D, and with an adjustable damper, G, all made and operating substantially as and for the purpose herein shown and described.

JAMES GRAY,
